DESIGN FOR A ROLLER SHADE BRACKET

Erven Krasemann, Sr., Milwaukee, Wis.

Application October 2, 1941, Serial No. 103,611

Term of patent 14 years

To all whom it may concern:

Be it known that I, Erven Krasemann, Sr., a citizen of the United States, residing at Milwaukee, in the county of Milwaukee and State of Wisconsin, have invented a new, original, and ornamental Design for Roller Shade Brackets, of which the following is a specification, reference being had to the accompanying drawing, forming part thereof.

The figure is a view in perspective of a roller shade bracket, showing my new design.

I claim:

The ornamental design for a roller shade bracket, as shown.

ERVEN KRASEMANN, SR.
